UNITED STATES PATENT OFFICE.

GEORGE J. CHARLAND, OF SANDPOINT, IDAHO.

SPRING APPLIER AND REMOVER.

1,342,529.

Specification of Letters Patent.

Patented June 8, 1920.

Application filed April 21, 1919. Serial No. 291,627.

To all whom it may concern:

Be it known that I, GEORGE J. CHARLAND, a citizen of the United States, residing at Sandpoint, in the county of Bonner and 5 State of Idaho, have invented certain new and useful Improvements in Spring Applicators and Removers, of which the following is a specification.

The present invention relates to improvements in spring applicators and removers, designed especially for use in connection with springs of tappet and similar valves, wherein the spring is to be compressed preparatory to removal from or application to the 15 stem of the valve, and particularly for the purpose of holding the spring pressed while the cotter pin is being removed when applying and to hold the spring in line when being applied.

20 The primary object of the invention is the provision of a device of this character by means of which the spring may be held in alinement in order to facilitate the application to and the removal from its seat of the spring and prevent accidental displacement of the spring.

To this end the invention contemplates the use of a pair of parallel levers carrying the clasping members or jaws for the spring, 30 combined with means for removing the levers toward or away from each other for compressing the spring or to permit it to expand, the levers being maintained at all times parallel with each other and the clasping jaws and levers moving in the same 35 parallel planes in axial alinement with the stem of the valve and its spring, thus holding the spring in axial alinement with the stem and preventing the spring from buckling and becoming displaced.

40 The invention consists in certain novel combinations and arrangements of these parallel levers and their jaws in connection with means for actuating the levers and 45 maintaining them in parallelism as will be described.

In the accompanying drawings I have 50 illustrated one complete example of the physical embodiment of my invention, the parts being combined and arranged according to the best mode I have so far devised for the practical application of the principles of my invention.

Figure 1 is a side view in elevation of the tool embodying the invention, showing it 55 in position of actual use, compressing the spring on the stem.

Fig. 2 is a top plan view of the tool of Fig. 1.

Fig. 3 is an end view of the tool, showing 60 particularly the pivoted hooked jaws on the pivoted head of the tool adapting the tool for use with different springs.

In the preferred embodiment of the invention as depicted in the drawings, I utilize 65 a pair of levers 1 and 2 that are of metal and of suitable size and shape, and these levers are normally and at all times in parallelism, and actuated through the instrumentality of the screw bar 3.

70 The screw bar is provided with both right hand threads and left hand threads and is turned by a hand wheel 4, but remains seated in the intermediate, fixed, connecting bar 5 which is provided with a slotted journal 75 6 for the screw bar to turn in. The relationship of the two levers and the intermediate bar is one of permanent parallelism, although of course the distance between the two levers and the intermediate bar is 80 changed by turning the screw bar when the spring 20 is to be compressed, or permitted to expand.

85 At one end, the levers are connected to the intermediate bar by a pair of links 7, 7, having a common pivot 8 on the intermediate bar, and pivoted at 9, 9, to the ends of the levers, while at the opposite end of the tool a pair of links 10, 10 are provided with a common pivot at 11 on the intermediate 90 bar and pivots 12, 12 on the levers. The links 7 and 10 are arranged in parallel pairs to swing on their pivots as the screw bar is turned and to maintain the levers in stable and fixed parallelism.

95 One of the levers, at its free end has an extension or forked end 13 with the open slot 14, forming a fixed clasping jaw for the spring, and coöoperating with this fixed jaw, which forms a seat for the spring, is a 100 flexible and adjustable device involving the two pivoted jaws 15, 15 formed with hooked ends 16 and pivoted on a bracket 17, which in turn is pivoted at 17' on the end of the lever 1. The bracket or head 17 is arranged 105 transversely of the lever and its pivot 17'

permits an oscillating movement of the head transversely of the lever, while the jaws, which are pivoted at 18 to the head, project beyond the head with their hooked ends 5 turned toward each other, and may oscillate on their pivots 18.

Thus the pivoted head 17 enables the tool to be applied, and with facility, to any ordinary angle of spring, and the two 10 pivoted jaws 15 adapt the device for different sizes of springs.

The operation of the tool is illustrated in Fig. 1 where the spring 20 is associated with the stem 19 of the valve, and the cup 15 21 forms the seat for the spring, the upper end of the spring being retained as usual by the cotter pin of the valve stem.

The forked end or fixed jaw of the tool is slipped under the cup 21 and around the 20 stem, and the two-hooked jaws 15 are turned on their pivots so that their hooks engage over the upper end of the spring. Now by turning the hand wheel 4, its right and left hand screws bring the two levers toward 25 each other, the links maintaining the levers in stable parallelism and the spring is compressed between the flexible jaw and the fixed jaw of the tool, the flexible jaw adapting itself to the spring and clasping the 30 spring with a secure and firm hold, while the fixed jaw forms a rigid seat for the lower end of the spring. In this manner the spring may be compressed for application to or removal from the valve devices, with-

out danger of displacement or disarrangement, and without harm to the operator. 35

What I claim is—

1. The combination with the pair of parallel levers, an intermediate fixed connecting bar, and links pivoted between said 40 levers and the bar, of a transverse screw bar operable in the fixed bar having right and left hand threads in the levers, and clasping jaws on the levers. 45

2. The combination with the pair of parallel levers, the intermediate bar, and the connecting links, of a transverse screw bar operable in the intermediate bar and having right and left hand threads in the levers, and spring clasping means on the levers, 50 one of which is fixed and the other flexible with relation to the levers.

3. The combination with the levers, links, intermediate bar and screw bar, of a fixed 55 jaw on one lever, and a flexible jaw on the other lever comprising a pivoted head on the lever and a pair of pivoted co-acting hooked members, as described.

4. The combination with the levers, intermediate bar, screw bar, and links, of a fixed 60 slotted jaw on one lever, a transversely pivoted head on the other lever, and a pair of outwardly projecting jaws pivoted at the sides of the fulcrum of the head and having inturned hooks, as described. 65

In testimony whereof I affix my signature,

GEORGE J. CHARLAND.
